UNITED STATES PATENT OFFICE.

JAMES S. THOMPSON, OF CHICAGO, ILLINOIS, ASSIGNOR TO EDWARD H. FALLOWS, TRUSTEE, OF NEW YORK, N. Y.

BRAKE-SHOE.

No. 838,222.

Specification of Letters Patent.

Patented Dec. 11, 1906.

Application filed April 3, 1906. Serial No. 309,686.

To all whom it may concern:

Be it known that I, JAMES S. THOMPSON, a citizen of the United States, and a resident of Chicago, in the county of Cook and State of Illinois, have made and invented certain new and useful Improvements in Brake-Shoes, of which the following is a specification.

My invention relates to an improvement in brake-shoes, and more particularly to those adapted for use upon locomotives and railway-cars and generally made of cast-iron, the object being to produce a shoe of this type or character which if broken in use the parts will still be held or bound together.

5 In my present invention the binding means consists of a rod, strap, or wire so bent or shaped as to form at one end an attaching hook or lug for the brake-head and at the opposite end a reinforcement for the metal surrounding the hole or opening formed in the shoe for the passage of the key-bolt, the bent rod taking the strain of said bolt and preventing the latter from coming in contact with the cast-iron part of the shoe and cracking or 25 breaking the shoe at that point, as is liable to occur when the bolt is allowed to impinge on the cast-iron or wearing body of the shoe, the extreme end or ends of the bent rod, if desired, forming an end stop for the brake-head.

30 With these and other ends in view the invention consists in certain novel features of construction and combinations of parts, as will be hereinafter fully described, and pointed out in the claims.

35 In the accompanying drawings, Figure 1 is a top plan view of a shoe constructed in accordance with my invention. Fig. 2 is a longitudinal sectional view taken on the line 2 2 of Fig. 1. Fig. 3 is a cross-sectional view 40 taken on the line 3 3 of Fig. 2. Figs. 4, 5, and 6 are views of modified forms of the invention.

45 Referring to the drawings, A represents a shoe of ordinary construction and formed of cast-iron or, if desired, of relatively hard and soft metals, as is frequently the case in order to obtain increased frictional and wearing qualities. In the body of the shoe is formed an opening B for the passage of a key-bolt, (not shown,) whereby to attach a brake-head. The formation of this hole or opening in the shoe necessarily weakens the same and renders the shoe liable to be broken or fractured should the key-bolt become loosened.

and allowed to jar or vibrate therein. In order to relieve the cast metal surrounding this opening of the strain of the bolt and prevent the impingement of the latter directly on the cast-iron, I reinforce the same with a rod or wire C, formed of wrought, ductile, or other tough metal and so bent or formed as to partially or entirely surround the opening, this rod or wire being located at or adjacent to the back of the shoe. As illustrated in Figs. 1, 2, and 3, the rod C is formed at one end with the loop D, bent or shaped to form a hook to engage with the brake-head, for the purpose of assisting in securing the latter to the shoe, the rod at the opposite end being bent partially around the opening B, and the portions of the rod after crossing each other are bent upwardly, as illustrated in Fig. 2, to form the end stop E. Instead of crossing the wire or rod on the outer side of the opening B the same may be crossed in front of said opening, as illustrated in Fig. 4, the rod or wire C' in such instance being also continued beyond the opening and bent to project up through the metal of the shoe and form the end stop E'. Again, as illustrated in Fig. 5, the rod or wire C' may be crossed both in front and to the rear of the opening B, in which instance said bolt-opening will be entirely surrounded and reinforced by the bent rod. Again, as illustrated in Fig. 6, the wire or rod may be continuous and passed around the bolt-opening B and forming at its opposite end the attaching-hook D'. It will of course be apparent without further description and illustration that the rod or wire C may be bent in various ways in order to accomplish the same object—that is, to form at one end of the shoe an attaching-hook, reinforce the metal surrounding the opening for the key-bolt, and, if desired, at the opposite end to form an end stop, and hence I do not limit my invention to the exact details shown and described; but,

Having fully described my invention, what I claim as new, and desire to secure by Letters Patent, is—

1. A brake-shoe formed with a bolt-opening in the body thereof and having a rod located at or adjacent to the back thereof, said rod being bent at one end to form an attaching-hook and at its opposite end to reinforce the metal surrounding said bolt-opening, substantially as described.

2. A brake-shoe formed with a bolt-opening through the body thereof and having a rod located at or adjacent to the back thereof, said rod being bent at one end to form a hook, and at its opposite end to form an end stop, said rod reinforcing the metal around the bolt-opening, substantially as described.
3. A brake-shoe formed with a bolt-opening through the body thereof, and provided with a rod at or adjacent to the back thereof, said rod being bent to form an end stop and reinforce the metal around said bolt-opening, substantially as described.
4. A brake-shoe formed with an opening through the body thereof, and having a rod

located at or adjacent to the back thereof, said rod being bent at one end to form an attaching-hook, and at the opposite end crossed, whereby the same reinforces the metal around said bolt-opening, the extreme ends thereof forming an end stop, substantially as described.

Signed at Chicago, in the county of Cook and State of Illinois, this 30th day of March, A. D. 1906.

JAMES S. THOMPSON.
